UNITED STATES PATENT OFFICE.

GERTRUDE CLINE AND AARON HORTON, OF COLEMAN, MICHIGAN; SAID CLINE
ASSIGNOR OF ONE-THIRD TO SAID HORTON.

WASHBOARD.

1,272,776.

Specification of Letters Patent. Patented July 16, 1918.

Application filed December 31, 1913. Serial No. 809,788.

To all whom it may concern:

Be it known that we, GERTRUDE CLINE and AARON HORTON, citizens of the United States, residing at Coleman, in the county of Mid-5 land and State of Michigan, have invented certain new and useful Improvements in Washboards, of which the following is a specification.

This invention relates to wash-boards, and 10 particularly to that class of wash-boards wherein means are provided for supporting a bar or bars of soap in position at the upper end of the wash-board so that the clothes may be rubbed against the soap rather than 15 the soap rubbed against the clothes.

The primary object of our invention is 20 the provision of a very simple and easily operated structure of this character adapted to support at the upper end of the wash-board one or more cakes or bars of soap and having means whereby the soap may be forced outward as used.

A further object of the invention is to so 25 construct the wash-board that the soap may be readily inserted in place, may be supported firmly against displacement and that provision may be made for proper drainage of water from the soap.

A further object of the invention is the 30 provision of means whereby a cake or cakes of soap may be fed forward by hand or automatically against the supporting wires or bars and thus projected into position to engage the clothes as they are rubbed upon 35 the board.

A further object of the invention is to provide means whereby the soap may be forced outward to any desired degree in order to increase the projection of the cakes of soap.

40 Still another object is to so form the means for feeding or projecting the soap that it will operate equally well whether one or more cakes or bars are used.

Other objects will appear in the course of 45 the following description.

Our invention is illustrated in the accompanying drawings, wherein:

Figure 1 is a perspective view of a wash-board constructed in accordance with our 50 invention.

Fig. 2 is a fragmentary vertical section through the upper end of the wash-board

showing the soap retaining and feeding means.

Fig. 3 is a transverse section on the line 55 3-3 of Fig. 2.

Fig. 4 is a face view of another form of our invention.

Fig. 5 is a vertical section therethrough on the line 5-5 of Fig. 4.

Fig. 6 is a transverse section on the line 60 6-6 of Fig. 5.

Corresponding and like parts are referred to in the following description and indicated in all the views of the accompanying drawings by the same reference characters.

Referring now particularly to Figs. 1, 2 and 3, 2 designates the wash-board generally, which may be formed in any suitable manner, but as shown, comprises the side members 3 connected by a transverse brace 4 and a head-board 5. Extending between the members 3 throughout the greater portion of the wash-board is the corrugated rubbing-plate 6, this rubbing plate 6 extending up to 75 the brace 4 and above the brace 4 and extending between the side-members 3 is the transversely extending flat plate, preferably of metal and designated 7. The upper end of this flat plate 7 extends into a kerf 8 formed in the head-board 5. This flat plate 70 8 extends entirely across the board as shown in Fig. 1 and is formed at its middle with a transversely extending opening 9 having a length nearly equal to the width of the board 85 and a width equal to the width of a bar or bars of soap. The lower edge of the plate 7 does not extend to the corrugated metal plate 6 or to the brace 4, but a space 10 is left, 90 forming a drain opening.

Mounted upon the rear of the wash-board rearward of the plate 7 is the housing 11. This is formed with a rear portion 12 which extends approximately parallel to the plate 7 and with a downwardly and forwardly extending bottom 13 which is preferably disposed at an angle of about 45° and which may or may not be continuous with the sheet metal or corrugated plate 6. The sides of the housing 11 are attached to the side members 3 in any suitable manner as by bolts, screws or nails 14. The hinged cover 15 closes the upper portion of the housing 11, this cover being hinged at 16 to the plate 12, and at its 95 100

upper end closes against a lip 17 projecting from the under side of the head-board 5. A latch 18 or other suitable device of this character is mounted upon the rear edge of the head-board 5 and engages over the free end of the hinged cover 15 to hold it closed.

As will be seen in Fig. 2 the plate 7 is formed with a rearwardly extending ledge or flange 19 which defines the lower wall 10 of the opening 9. Mounted upon the plate 7 and extending transversely across the opening 9 are a plurality of soap retaining wires or bars 20. The vertical portions of each wire or retaining member 20 is disposed parallel to the plate 7 and each wire is formed at its lower end with a horizontal rearwardly extending portion 21 which rests upon and is supported upon the ledge 19, the rear end of the horizontal portion being 15 downwardly bent as at 22 and inserted in a corresponding opening formed for it in the ledge or flange 19. The upper end of each rod or wire 20 is inwardly bent as at 23 then upwardly extended and outwardly bent 20 as at 24 and this projecting end is inserted in a corresponding opening formed in the plate 7. As these members are preferably constructed of resilient wire they may be independently assembled in position by inserting the lower ends 22 in the perforations in the ledge 19 and then inserting their upper ends 24 in the perforations in the plate 7. The lower long horizontal arm 21 under these circumstances acts as a base and 25 the resilience of the vertical portion of the member 20 will cause the upper end thereof to be forcibly projected into the openings of the plate 7. Under these circumstances the rods, wires or bars 20 cannot turn laterally. 30 The cake or bar of soap 25, or a plurality of cakes or bars, as the case may be, are positioned upon the horizontal portions 21 of the members 20, and are resiliently held between these portions and the horizontal portions 23 of the members 20. It is to be noted 35 at this point that the portions 21 of the members 20 support the cake of soap above the upper face of the ledge 19 and thereby permit any water to drain off the soap and 40 from the ledge.

Disposed rearward and against the cakes of soap is a follower-plate 26. This plate has a length equal to the length of the opening 9 and is disposed vertically within the 45 housing 12. Formed or mounted upon the rear face of the plate 26 is a boss 27 having a central perforation or recess for the reception of the inner end of a screw-rod 28 which extends out through a central opening 50 in the rear plate 12 of the housing 11. Surrounding this screw-threaded rod 28 is a sleeve 29 which has screw-threaded engagement with the rod 28 but its outer face is 55 smooth. The outer end of the sleeve supports a hand-wheel 30 while the inner end 60

of the sleeve is headed or flanged as at 31 to form a limiting stop. Mounted upon the plate 12 and surrounding the sleeve 29 and snugly fitting the same is a bushing 32 which is flanged as at 33 to provide a firm 70 engagement with the plate 12 to reinforce this plate. This bushing is relatively long and projects outward beyond the plate 12 to thereby provide a firm bearing for the sliding sleeve 29.

Disposed within the housing 11 is a coil-spring 34, one end of which bears against the member 27 while the other end bears against the flange 33 of the bushing 32.

In use, one or more cakes of soap are 80 placed in the opening 8 resting upon the inwardly extending legs 21 of the retaining members 20, the soap being easily put in place by inserting the soap through the opening normally closed by the door 15, the 85 head or plate 26 being moved rearwardly whereby to permit the soap to be disposed in place against the bars or rods 20. After the soap is in place the handle 30 is released, thus permitting the spring 34 to force the 90 follower 26 against the soap. Where the soap is relatively soft the spring 34 will exert sufficient pressure to so force the soap against the bars as to cause the soap to be cut by the bars and feed therethrough. 95 Where, however, the soap is hard it is necessary to first force the soap forward by turning the wheel 30 until the bars 20 have initially cut into the soap and then as the soap is used the water will soften the soap to 100 a certain extent which will permit the spring 34 to gradually feed the soap outward, thus effecting an automatic feed of soap as it becomes worn away during use. It is to be noted here, that as the sleeve 29 has sliding 105 engagement with the bushing 32 the sleeve and hand-wheel will move inward with the inward movement of the follower 26 and that if at any time it is desired to forcibly feed the soap outward, if the automatic feed 110 does not work properly, then it is only necessary to turn the hand-wheel to a slight amount. If the action of the spring grows weaker, to such an extent that the soap will not feed properly and automatically, then 115 the hand-wheel may be used from time to time to force the soap outward. Inasmuch as the soap is held firmly by the retaining wires and against the follower plate it may be used until a very thin remainder of the 120 cake is left.

In Figs. 4, 5 and 6 we show another and simpler form of our mechanism, and what we believe to be a preferable form in many respects. The wash-board itself is constructed in the same manner as previously described, with side-bars 2 and a head-board 5, a transverse brace 4 and a corrugated metal rubbing portion 6. It is likewise provided with a plate 35 which is of the same 130

character as the plate 7, heretofore described, but not of the same detail construction. This plate is approximately flush with the rubbing portion 6 of the board and is formed 5 with an opening 36 extending transversely across it nearly the entire width of the board between the members 2. The plate 35 at the upper wall of the opening 36 is reinforced by turning the plate over a transversely extending wire or rod 37. The plate 10 35 below the opening 36 extends downward nearly to the corrugated portion 6 so as to leave a transversely extending space or slot 37 for drainage purposes. The lower wall of 15 the opening 36 is formed with an inwardly extending ledge 38. The housing 39 has approximately the same form as that illustrated in Fig. 2 and is made of sheet metal and preferably continuous with the sheet 20 metal or corrugated portion 6. The upper end of this housing is upwardly inclined as at 40 and then extends underneath and against the under surface of the head-board 5. It is then folded to provide a bead 41 25 which extends into a kerf 32 formed in this head-board. Preferably the plate 35 is continuous with the housing, as illustrated in Fig. 5 and thus the whole metallic portion of the board may be formed from one piece 30 of sheet metal. This we regard as having important advantages over the construction shown in Fig. 2. The upwardly and forwardly extending portion 40 of the housing is formed with an opening 43 closed by a 35 removable lid or cover 44, this opening being large enough to permit the introduction of soap into the housing and its proper disposition upon the soap receiving bars. Preferably the metal which is cut away to form 40 the opening 36 in the plate 35 is bent rearward to form the shelf or ledge 38 and is then folded downward as at 45 and soldered or otherwise attached to the upwardly inclined bottom wall of the housing 39. This 45 portion 45 of the ledge or flange 38 is perforated or cut away at a plurality of points to form drainage openings whereby any water which may pass from the soap or which will pass into the opening 36 may 50 drain downward along the bottom wall of the housing and out through the slot 37.

Extending across the opening 36 are a plurality of soap retaining rods, bars, or wires 46. These extend vertically and at their 55 upper ends are inwardly bent as at 47 and the extremity of this inwardly bent portion is bent around or otherwise connected to the rod 37. The lower ends of the wires or rods 46 are inwardly bent as at 48 and are soldered or otherwise connected to the ledge 38 so as to lie flat thereon.

Mounted within an opening in the rear wall of the housing 39 is a thimble 49 having its base formed with a flange 50 which 60 bears against the rear wall of the housing, 65

the body of the thimble extending out through the aperture of the housing and projecting rearward relatively a considerable distance. Passing through this thimble is a screw-threaded rod 51 which is smaller 70 in diameter than the thimble and does not engage therewith, this rod being preferably of such length that it extends to a plate located in the series of vertical rods or wires 46. The extremity of the rod is formed with a 75 socket 52 to receive a pin 53 projecting inward from a vertical bar or rod 54 which is disposed at the middle of the opening 36 and which is attached to the plate 35 in the same manner as are the wires or rods 46. 80

Mounted upon the screw-threaded rod 51 and engaging the screw threads thereof is a nut 55 having a relatively long bearing upon the rod 51 and having flanges bearing against a follower-plate 56 which extends 85 transversely nearly the full length of the housing and which is adapted to bear against the cakes of soap 57, as will be seen clearly in Fig. 6. The rear end of the screw-threaded rod 51 carries a hand-wheel 58 and 90 mounted upon the rod in any suitable manner is a collar 59 which is keyed to the screw.

It will be seen that the feed-screw 51 is rigidly supported at both ends and that when rotated by the hand-wheel 58 it will 95 carry the nut 55 back and forth, depending upon the direction of rotation of the hand-wheel. It will also be noted that the rear end of the nut 55 when fully retracted by the feed screw enters the inner end of the 100 thimble 49. This allows a relatively long nut to be used in a relatively small space, the object being to secure a firm bearing for the nut upon the screw-threaded rod.

A brace-rod 60 is disposed directly above 105 the screw in line with the screw-threaded rod 51 so as to pass between the bars or cakes of soap and acts to prevent the rear wall of the housing 39 and the front wall of the housing formed by the plate 35 from 110 springing farther apart when the force of the screw is used to feed forward very hard soap.

It will be noted that in the operation of the device all that is necessary to place the soap in position is to turn the hand-wheel 58 back, thus retracting the follower 56 sufficiently to permit the soap to be dropped in from the top, then the hand-wheel is turned in a reverse direction forcing the follower 115 against the soap. The soap may then be forced forward until the wire or rods 46 embed themselves slightly in the soap. This will leave the full face of the soap exposed to the clothes when rubbed over it and as the soap wears away it may be fed forward 120 by a slight turn of the hand-wheel 58.

As illustrated, only two bars of soap 57 are shown, but the number of bars used 125 will, of course, depend on the size of the 130

cakes or bars, and as the follower plate is rigidly carried by the nut 55 it will act equally well where one bar of soap is used disposed on one side only of the wash-board.

It will be seen that our invention is simple, easily operated, may be cheaply manufactured and results in a great economy in the soap used.

10 The soap is firmly supported so that it cannot get out of place even when worn down to a very thin layer and the device is such as to greatly reduce the labor incident to washing clothes.

15 What we claim is:

1. A washboard including a rubbing plate having a soap exposing opening, means for supporting a cake of soap in said opening, a follower, a screw engaging the follower and operable to positively and forcibly feed the soap against said supporting means and

through said opening, and a spring engaging said follower to automatically feed the soap independently of the screw.

2. A washboard including a rubbing plate 25 having a soap exposing opening, means for supporting a cake of soap in said opening, a follower disposed behind the opening, a screw threaded rod connected to the follower, a screw threaded sleeve engaging the 30 rod, an operative support for the sleeve and through which the sleeve is slidale, and a spring engaging said support and bearing against the follower.

In testimony whereof we affix our signatures in presence of two witnesses.

MRS. GERTRUDE CLINE. [L. S.]
AARON HORTON. [L. S.]
